The ornamental design for a multi-directional rotary-pawl latch, as shown and described.

DESCRIPTION

FIG. 1 is a perspective view of a multi-directional rotary-pawl latch embodying our new design, showing the handle in a folded-down position and the lower housing in a first angular orientation relative to the upper housing;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the multi-directional rotary-pawl latch of FIG. 1 showing the handle in the raised position;

FIG. 9 is a front view of the multi-directional rotary-pawl latch of FIG. 8;

FIG. 10 is a rear view of the multi-directional rotary-pawl latch of FIG. 8;

FIG. 11 is a right side view of the multi-directional rotary-pawl latch of FIG. 8;

FIG. 12 is a left side view of the multi-directional rotary-pawl latch of FIG. 8;

FIG. 13 is a top view of the multi-directional rotary-pawl latch of FIG. 8;

FIG. 14 is a bottom view of the multi-directional rotary-pawl latch of FIG. 8;

FIG. 15 is a perspective view of the multi-directional rotary-pawl latch of FIG. 1, showing the handle in a folded-down position and the lower housing in a second angular orientation relative to the upper housing;

FIG. 16 is a front view thereof;

FIG. 17 is a rear view thereof;

FIG. 18 is a right side view thereof;

FIG. 19 is a left side view thereof;

FIG. 20 is a top view thereof;

FIG. 21 is a bottom view thereof;

FIG. 22 is a perspective view of the multi-directional rotary-pawl latch of FIG. 15 showing the handle in the raised position;
FIG. 23 is a front view of the multi-directional rotary-pawl latch of FIG. 22;
FIG. 24 is a rear view of the multi-directional rotary-pawl latch of FIG. 22;
FIG. 25 is a right side view of the multi-directional rotary-pawl latch of FIG. 22;
FIG. 26 is a left side view of the multi-directional rotary-pawl latch of FIG. 22;
FIG. 27 is a top view of the multi-directional rotary-pawl latch of FIG. 22;
FIG. 28 is a bottom view of the multi-directional rotary-pawl latch of FIG. 22;
FIG. 29 is a perspective view of the multi-directional rotary-pawl latch of FIG. 1, showing the handle in a folded-down position and the lower housing in a third angular orientation relative to the upper housing;
FIG. 30 is a front view thereof;
FIG. 31 is a rear view thereof;
FIG. 32 is a right side view thereof;
FIG. 33 is a left side view thereof;
FIG. 34 is a top view thereof;
FIG. 35 is a bottom view thereof;
FIG. 36 is a perspective view of the multi-directional rotary-pawl latch of FIG. 29 showing the handle in the raised position;
FIG. 37 is a front view of the multi-directional rotary-pawl latch of FIG. 36;
FIG. 38 is a rear view of the multi-directional rotary-pawl latch of FIG. 36;
FIG. 39 is a right side view of the multi-directional rotary-pawl latch of FIG. 36;

FIG. 40 is a left side view of the multi-directional rotary-pawl latch of FIG. 36;
FIG. 41 is a top view of the multi-directional rotary-pawl latch of FIG. 36;
FIG. 42 is a bottom view of the multi-directional rotary-pawl latch of FIG. 36;
FIG. 43 is a perspective view of the multi-directional rotary-pawl latch of FIG. 1, showing the handle in a folded-down position and the lower housing in a fourth angular orientation relative to the upper housing;
FIG. 44 is a front view thereof;
FIG. 45 is a rear view thereof;
FIG. 46 is a right side view thereof;
FIG. 47 is a left side view thereof;
FIG. 48 is a top view thereof;
FIG. 49 is a bottom view thereof;
FIG. 50 is a perspective view of the multi-directional rotary-pawl latch of FIG. 43 showing the handle in the raised position;
FIG. 51 is a front view of the multi-directional rotary-pawl latch of FIG. 50;
FIG. 52 is a rear view of the multi-directional rotary-pawl latch of FIG. 50;
FIG. 53 is a right side view of the multi-directional rotary-pawl latch of FIG. 50;
FIG. 54 is a left side view of the multi-directional rotary-pawl latch of FIG. 50;
FIG. 55 is a top view of the multi-directional rotary-pawl latch of FIG. 50; and,
FIG. 56 is a bottom view of the multi-directional rotary-pawl latch of FIG. 50.
